176,879

COCKTAIL TABLE

William B. Petzold, Coshocton, Ohio, assignor to General
Electric Company, a corporation of New York

Application July 14, 1954, Serial No. 31,420

Term of patent 14 years

(Cl. D33—14)

Fig. 1

Fig. 2

Figure 1 is a perspective view of a cocktail table embodying my new design; and

Figure 2 is an end view of the longer side of the table.

I claim:

The ornamental design for a cocktail table, as shown.

References Cited in the file of this patent

Gift and Art Shop, September 1930, page 34, No. 3, two trays at lower left of page.

Decorative Furnisher, October 1936, page 23, cocktail
table in bottom group; December 1936, page 26, cocktail
table in bottom group.

Home Furnishings Merchandising, September 1948, page 46, legs on cases at bottom left of page.

Home Furnishings, January 1953, page 71, cocktail
table at center left by Period Tables Inc.

Furniture Age, February 1953, page 24, cocktail table in Modern grouping illustrated at top of page.